[57] CLAIM

The ornamental design for a volleyball net tensioning device, as shown and described.

DESCRIPTION

FIG. 1 is a front elevational view of a volleyball net tensioning device showing my new design, the broken lines being for illustrative purposes only;

FIG. 2 is a side elevational view taken from the right hand side of FIG. 1.

FIG. 3 is a rear elevational view thereof.

FIG. 4 is a side elevational view taken from the left hand side of FIG. 3.

FIG. 5 is a top plan view thereof.

FIG. 6 is a bottom plan view thereof.

FIG. 1

FIG. 2

FIG. 3

FIG. 4

FIG. 5

FIG. 6
